SMOKE ALARM

Frederick G. Mackay, Tarzana, Calif., assignor to
Teledyne Water Pik, Fort Collins, Colo.

Filed Oct. 31, 1975, Ser. No. 627,710

Term of patent 14 years

Int. Cl. D10—05

U.S. Cl. D10—106

Fig. 1

Fig. 2

Fig. 3

Fig. 4

FIG. 1 is a bottom plan view of a smoke alarm embodying my new design;

FIG. 2 is a side-elevational view thereof;

FIG. 3 is a top plan view thereof; and

FIG. 4 is a perspective view thereof.

The side-elevational view opposite that shown in FIG. 2 is, in essential outline, the same as is shown in FIG. 2. I claim:

The ornamental design for a smoke alarm, as shown and described.
